FUEL PRESSURE RELEASE AND VALVE THEREFOR

Paul C. Murrah, Corinth, Miss.

Application August 12, 1955, Serial No. 528,220

12 Claims. (Cl. 123—139)

The present invention relates in general to pressure relief apparatus, and more particularly to apparatus for relieving excessive pressure in the fuel feed line of an internal combustion engine between the fuel pump and the carburetor thereof.

This application is a continuation-in-part of my co-pending application Ser. No. 460,609, filed October 6, 1954, and now abandoned.

In conventional internal combustion engines, the fuel pump supplies fuel to the carburetor at a pressure of several pounds to the square inch. The conventional fuel pump includes a diaphragm associated with intake and outlet valves, a diaphragm actuating cam lever controlled by a cam driven in accordance with rotation of the engine cam shaft for shifting the diaphragm through its intake stroke, and a diaphragm return spring which is compressed on the intake stroke and supplies power for the pumping stroke of the diaphragm. The admission of fuel from the fuel feed line to the carburetor is controlled by a float valve which should maintain a specific fuel level in the carburetor at all times. To achieve proper starting characteristics of the internal combustion engine, the carburetor float valve should also hold the specific fuel level in the carburetor after the engine has ceased operation and consumption of fuel fed to the carburetor has terminated, in order to prevent fuel from overflowing through the carburetor intake nozzle and other passages into the intake manifold which produces a rich or engine-flooding fuel condition making it difficult to start the engine.

In practice, it has been found that the carburetor and intake manifold of internal combustion engines frequently become flooded in a short time after the engine is stopped, as a volume of fuel becomes trapped in the fuel line between the fuel pump and carburetor when the engine stops and the force of the diaphragm return spring in the fuel pump urges the diaphragm toward the fuel pump inlet and outlet valves and pumps the fuel trapped in the feed line into the carburetor intake manifold. Although this movement of the fuel pump diaphragm is only to the extent permitted by the diaphragm actuating cam lever as it is shifted under the dominating force of the diaphragm return spring from the high point on its associated cam to the lower point on the cam at which the cam shaft stops, this movement is frequently sufficient to flood the carburetor and intake manifold. Residual pressure in the fuel feed line after the engine stops, arising from the fact that fuel pumps provide somewhat greater pressure than is necessary to feed the fuel, is another suspected cause of this flooding.

Further, under current design practice, the temperature in the upper regions under the hood of an automobile adjacent the carburetor and fuel lines is increased for a short time after the engine ceases operation due to termination of the flow of air through the cooling system and the excess heat that rises into the region from the exhaust manifold and engine, this region being poorly

2

ventilated. This increased temperature further boosts the pressure head in the fuel line supplying the carburetor, thereby further implementing the expansion of fuel trapped between the fuel line and carburetor into the carburetor and the consequent establishment of the flooding conditions.

An object of the present invention, therefore, is the provision of apparatus associated with internal combustion engines which is conditioned upon cessation of engine operation to maintain preselected static fuel conditions in the fuel supply line to the engine carburetor while the engine is idle and thereby improve starting characteristics of the engine.

Another object of the present invention is the provision of apparatus associated with internal combustion engines which is activated in response to cessation of engine operation and deactivated in response to starting of the engine to regulate fuel pressure conditions in the feed line to the carburetor and prevent fuel expansion into the carburetor establishing a flooded condition therein while the engine is idle.

Another object of the present invention is the provision of apparatus associated with internal combustion engines which is responsive to conditions incident to the idle state of an internal combustion engine to regulate pressure conditions in the fuel feed line to the engine carburetor while the engine is idle and prevent delivery of fuel into the carburetor which would establish a flooding condition impairing starting characteristics.

Another object of the present invention is the provision of apparatus associated with internal combustion engines which is responsive to and activated by the pressure conditions in the intake manifold when the engine is idle to relieve the pressure in the fuel line supplying the carburetor and prevent delivery of fuel into the carburetor which would flood the carburetor.

Another object of the present invention is the provision of apparatus associated with internal combustion engines which is responsive to open-circuiting of the ignition switch associated with the engine and activated upon open-circuiting of the switch to relieve the pressure head in the fuel line supplying the carburetor and prevent delivery of the fuel to the carburetor and prevent delivery of the fuel to the carburetor while the ignition switch is open-circuited.

Another object of the present invention is the provision of apparatus associated with internal combustion engines activated by pressure conditions present when the engine is idle to relieve the pressure in the fuel line supplying the carburetor to prevent delivery of fuel into the carburetor, wherein means are provided to maintain the apparatus de-activated during transitory variations in such pressure conditions during operation of the engine.

Other objects, advantages and capabilities of the present invention will become apparent from the following detail description, taken in conjunction with the accompanying drawings showing several preferred embodiments of the invention.

In the drawings:

Figure 1 is a systematic view of fuel pressure relief apparatus embodying the present invention in association with the pertinent components of internal combustion engine fuel system, the pressure relief apparatus being illustrated in section;

Figure 2 is a view, partly in elevation and partly in section, showing a modified form of the present invention;

Figure 3 is a view, partly in elevation and partly in section, showing another modified form of the present invention; and,

Figure 4 is a view, partly in elevation and partly in

section, showing another modified form of the present invention.

Referring to the drawings, wherein like reference characters designate the corresponding parts throughout the several figures, and particularly to Figure 1, there is illustrated a conventional carburetor 10, an intake manifold 11, a fuel pump 12 and an oil pump 13 constituting the pertinent components in the fuel supply system of an internal combustion engine with which the apparatus of the present invention is designed to be associated, the fuel pump 12 supplying conventional fuel through the feed line 14 to the conventional float valve chamber of the carburetor 10.

As will be understood by those skilled in the art, the conventional fuel pump 12 associated with internal combustion engines includes a reciprocative diaphragm which is associated with intake and outlet valves in the fuel pump housing in such a manner that upon movement of the diaphragm away from the valves, a charge of fuel is delivered to the fuel pump from the gasoline tank of the vehicle, and upon return of the diaphragm toward the valves, the intake valve is closed by the pressure produced in the fuel pump created by the approaching diaphragm and the charge of fuel in the fuel pump is pumped through the feed line 14 to the carburetor 10. The diaphragm is actuated during its charging or withdrawing stroke by means of a cam lever actuated by a cam driven from the cam shaft of the internal combustion engine, and a diaphragm return spring is associated with the diaphragm to be compressed during this charging or withdrawing stroke of the diaphragm and to be released when the cam lever passes the high point on its associated cam to supply power for the pumping or approaching stroke of the diaphragm. When the internal combustion engine ceases operation, the diaphragm return spring is frequently in a compressed condition with a charge of fuel in the fuel pump, and the force of this spring is such that it can drive the diaphragm through a substantial portion of the pumping stroke to expel fuel through the feed line 14 to the carburetor 10 while the engine is in process of achieving a static condition, this pumping movement of the diaphragm being in accordance with the movement permitted upon rotation of the cam by the force of the diaphragm return spring from the position wherein the high point of the cam engages the cam lever to the lower point on the cam at which the cam shaft completely ceases rotation. This action of the fuel pump diaphragm produces a high pressure head in the feed line 14 which overcomes the desired fuel level regulating action of the carburetor float valve and produces an enriched fuel condition in the carburetor and intake manifold which will interfere with proper restarting characteristics of the engine.

The pressure relief apparatus of the present invention is designed to relieve the pressure condition thus created in the feed line 14 and prevent this influx of fuel into the carburetor 10. In the embodiment illustrated in Figure 1, the pressure relief apparatus is indicated generally by the reference character 15 and includes an expansion chamber 16 and a regulating chamber 17 interconnected together. The expansion chamber 16 is formed as a closed housing by means of a cylindrical housing portion 18 of relatively large diameter having a smaller diameter integral cylindrical projection 19 extending from the rear thereof and a connecting integral frusto-conical portion 20 flaring outwardly from the cylindrical portion 19 and forming a portion of the wall of the regulating chamber 17. The larger diameter cylindrical portion 18 is peripherally flanged at its forward open end, to which a frusto-conical front cover 21 is secured to form the closed expansion chamber 16, the cover 21 being connected with an intake tube 22 which communicates with the feed line 14 through a T-fitting 23 on the feed line 14. A flexible diaphragm 24 is pro-

vided in the expansion chamber 16 and is peripherally supported between the adjacent edges of the expansion chamber housing portions 18 and 21. A frusto-conical member 25 cooperates with the frusto-conical portion 20 to form a complete enclosure for the regulating chamber 17, a flexible diaphragm 26 being marginally supported within the regulating chamber 17 between the cover member 25 and cover portion 20.

A connecting rod 27 is interconnected between the diaphragms 24 and 26 to coordinate movement thereof, the forward end of the rod 27 having a reduced end 28 which projects through a frusto-conical support and guide 29 corresponding in diameter to the internal diameter of the rear cylindrical body portion 18 and slidably therein, and through the diaphragm 24, a washer 30 being fitted about the reduced rod portion 28 and a nut 31 being threaded thereto to couple the diaphragm 24 to the forward end of the rod 27. The rear end of the rod 27 is provided with a reduced portion 32 which passes through the diaphragm 26, a supporting plate 33, and a washer 34, a nut 35 being threaded onto the reduced rod portion 32 to secure the same to the diaphragm 26. A vacuum seal 36 is fitted about an intermediate portion of the connecting rod 27 and is located within the intermediate smaller diameter cylindrical body portion 19 to isolate the chamber 17 from the expansion chamber 16. A conduit 37 extends from the cover portion 20 of the regulating chamber 17 to the intake manifold 11 to expose the front face of the diaphragm 26 to the vacuum conditions in the intake manifold 11.

The regulating chamber 17 may, if desired, be provided with a secondary chamber 38 connected through a conduit 39 to the oil pump 13 of the internal combustion engine to expose the rear face of the diaphragm 26 opposite that face exposed to the intake manifold conditions to the oil pressure conditions.

In the operation of this embodiment, the diaphragms 24 and 26 are located in the positions illustrated in Figure 1 when the engine is idle and the pressure conditions in the intake manifold 11 are at approximately atmospheric pressure. When the engine commences operation, the vacuum produced in the cylinders of the internal combustion engine establishes a negative pressure condition in the intake manifold 11 which is coupled to the regulating chamber 17 through the conduit 37, drawing the regulating chamber diaphragm 26 to the right as viewed in Figure 1. This movement of the regulating chamber diaphragm 26 is imparted to the expansion chamber diaphragm 24 through the connecting rod 27, thereby reducing the volume in the portion of the expansion chamber 16 lying to the right of the diaphragm 24. When the engine ceases operation, the pressure in the intake manifold 11 rises toward atmospheric pressure, forcing the regulating chamber diaphragm 26 toward the left to the position illustrated in Figure 1 which movement is communicated to the expansion chamber diaphragm 24 to increase the volume to the right of the diaphragm 24 in communication through the intake tube 22 with the feed line 14. This expansion of the volume in the expansion chamber 16 communicating with the feed line 14 is sufficient to relieve the pressure head existing in the feed line 14 due to the terminal pumping action of the fuel pump 12 and the thermal expansion of the fuel in the feed line 14 due to the increased temperature under the hood of the vehicle so as to prevent delivery of fuel into the carburetor and therefore avoid flooding conditions which would interfere with proper starting of the engine.

In order to provide trouble-free operation and prevent interference with normal fuel supply to the carburetor 10 during transitory variations in intake manifold pressure as when the internal combustion engine is heavily loaded by the vehicle travelling up an incline, the secondary regulating chamber 38 responsive to oil pressure

in the internal combustion engine is provided to dampen the transitory effect on the regulating chamber diaphragm 26 which the temporary reduction in the intake manifold pressure would produce. During such temporary heavy loading of the internal combustion engine, the increase in oil pressure is sufficiently related to the loss of intake manifold vacuum so that the increased pressure on the rear face of the regulating chamber diaphragm 26 during such periods substantially balances out the increased pressure on the front face of the regulating chamber diaphragm 26 to prevent any substantial expansion in the volume of that portion of the expansion chamber 16 in communication with the fuel feed line 14.

A second embodiment of the present invention is illustrated in Figure 2 wherein the expansion chamber diaphragm is electromagnetically disabled from relieving the pressure head in the fuel feed line while the ignition switch associated with the internal combustion engine is "on." The fuel pressure relief apparatus of this embodiment is indicated by the reference character 40, and is associated with a carburetor 10 supplying an intake manifold 11, a fuel pump 12 having inlet and outlet valves 12a and 12b, respectively, a fuel feed line 14 extending from the fuel pump outlet valve 12b to the carburetor 10, and a fuel supply line 41 extending from the fuel tank (not shown) to the fuel pump inlet valve 12a.

The expansion chamber 42 is formed of a pair of mating housing members 43 and 44 forming a closed chamber and supporting therebetween within the chamber a flexible diaphragm 45. A conduit 46 extends from the intake manifold 11 to the section of the chamber 42 below the diaphragm 45 to subject the lower diaphragm face to the pressure in the intake manifold 11. The upper housing member 43 is provided with a check valve extension 47 having a valve seat conduit 48 extending therethrough in communication with the chamber area above the diaphragm 45 and a ball check valve 49 seated thereon. The upper end of the valve seat conduit 48 remote from the diaphragm is connected through a tube 50 with the fuel line 14. A feedback conduit 51 also extends from the upper chamber section of expansion chamber 42 to the line 41 supplying the fuel pump.

A check valve plunger 52 slidably extending through supporting plates 53 on opposite faces of the diaphragm 45 and having a shoulder bearing on the uppermost plate 53 projects into the valve seat conduit 48 in operative relation with the check valve 49. A reduced diameter lower end of the plunger 52 is surrounded by a return spring 54 bearing against the lower wall of the housing member 44 and the lower plate 53 to urge the plunger 52 upwardly.

Magnetizable core members 55 depend from the lower diaphragm supporting plate 53 and are each surrounded by electromagnetic coils 56 fixed on the housing member 44 and connected in series relation with the ignition circuit lead 57 of the ignition switch 58 of the engine to be energized from the battery or generator only when the ignition switch is "on."

In the operation of this embodiment, the portion of the expansion chamber 42 below the diaphragm 45 is responsive to the pressure conditions in the intake manifold to draw the diaphragm 45 and plunger 52 downwardly to the position illustrated in Figure 2 wherein the check valve 49 is gravity-seated on its associated seat in the conduit 48 to close off this conduit. When the engine ceases operating, the rising pressure in the intake manifold 11 communicated to the lower diaphragm face through the conduit 46 elevates the central portion of the diaphragm 45 and the plunger 52 thereon to lift the check valve 49 off its associated seat. A return path for relief of fuel pressure from the fuel line 14 to the supply line 41 is then provided through the tube 50, the valve seat conduit 48, the upper section of the expansion

chamber 42 and the feedback line 51, by which the formation of any such fuel pressure head in the fuel line 14 which would flood the carburetor is prevented.

The electromagnetic components associated with this structure are to prevent transitory variations in intake manifold pressure from actuating the diaphragm 45 in such a manner as to interfere with proper fuel feed. When the ignition switch 58 is "on," the current in the electromagnetic coils 56 sets up a magnetic field attracting the core members 55 to such an extent that the reductions in intake manifold vacuum when the engine is loaded which are somewhat less than total vacuum collapse, are insufficient to overcome the magnetic attraction and force the diaphragm 45 and plunger 52 to valve unseating position.

Figure 3 illustrates a further embodiment operating generally on the same principle as that illustrated in Figure 2 but wherein the pressure relief apparatus components are incorporated into a single assembly with the fuel pump. In this embodiment, there is provided in the lower portion of a housing 60 the conventional fuel pump components including a pumping chamber 61 terminated at its lower end by a reciprocative flexible diaphragm 62 from which a diaphragm control plunger 63 depends, the plunger being reciprocated by a pivotal fuel pump operating lever 64 controlled by the fuel pump cam 65 on the cam shaft of the engine. Resiliently biased intake valve 66 and outlet valve 67 are provided in the upper wall of the pumping chamber 61 and are controlled by the pressure conditions created in the pumping chamber 61 by the fuel pump diaphragm 62. The fuel pump inlet valve 66 is seated in an inlet conduit 68 which communicates with the supply line 69 extending from the fuel tank or reservoir (not shown) and the outlet valve 67 is seated in an outlet conduit 70 in the housing 60 which communicates with the fuel feed line 71 extending to the carburetor 10.

A by-pass conduit 72 extends through the housing 60 between the inlet conduit 68 and the outlet conduit 70, at an intermediate point in which a pressure relief valve 73 is provided which is resiliently biased to closed condition. The intermediate portion of the by-pass conduit 72 is further provided immediately above the pressure relief valve 73 with an enlarged expansion chamber 74, across the upper portion of which in non-intercepting relation with the by-pass conduit 72 is a flexible diaphragm 75 having a depending plunger 76 affixed thereto and extending into operative relation with the pressure relief valve 73 to unseat the pressure relief valve 73 when the diaphragm 75 is forced downwardly under atmospheric pressure conditions at the upper face of the diaphragm. A conduit 77 extends from the upper portion of the expansion chamber 74 above the diaphragm 75, which is hereinafter termed the regulating chamber 78 and which, in the embodiment shown herein, is formed in a capping member 79 affixed to the housing body 60, to the intake manifold 11 to subject the upper surface of the diaphragm 75 to the pressure conditions in the intake manifold. Also disposed within the regulating chamber 78 is an electromagnetic coil 80 surrounding a fixed magnetizable core 81 disposed to attract the diaphragm plunger 76 when the core 80 is energized. The electromagnetic core 80 is connected through the wire 82 in series circuit relation with the conventional ignition switch of the internal combustion engine in the same manner as that illustrated in Figure 2 so as to maintain the electromagnetic coil 80 energized while the ignition switch is "on."

The operation of this embodiment is identical with that described in connection with Figure 2, the existence of low pressure conditions in the intake manifold 11 when the engine is operating being communicated through the tube 77 to the regulating chamber 78 to draw the diaphragm 75 upwardly to the position illustrated in Figure 3 wherein the diaphragm plunger 76 is free of contact with the pressure relief valve 73 so that the valve 73

is resiliently held against its associated valve seat to close off the by-pass conduit 72. When the engine ceases operating and the vacuum in the intake manifold 11 collapses, the resulting atmospheric pressure communicated to the upper face of the diaphragm 75 flexes the diaphragm downwardly to shift the plunger 76 so as to unseat the by-pass pressure relief valve 73 and open the by-pass conduit 72. In this condition, the fuel pressure head in the fuel feed line 71 and outlet conduit 70 is relieved through the by-pass conduit 72 to the inlet conduit 68 and supply line 69 to prevent existence of such pressure conditions in the fuel feed line 71 as would cause the carburetor to become flooded. The electromagnetic coil 70 which is energized when the ignition switch is "on" supplies sufficient magnetic attraction to the plunger 76 to overcome the small transitory increases of pressure in the intake manifold 11 when the engine is heavily loaded so as to prevent opening of the by-pass conduit 72 during such transitory operating conditions of the engine and prevent interruption of normal fuel supply at such times.

Figure 4 illustrates another embodiment wherein transitory fluctuations in manifold pressure are prevented from relieving fuel pressure in the fuel feed line by a lockout mechanism operative when the throttle valve of the engine is open. The expansion chamber and regulating chamber are integrated into one assembly in a housing 85 of mating sections having a flexible diaphragm 86 marginally supported therebetween dividing the interior of the housing 85 into an upper expansion or by-pass chamber 87 and a lower regulating chamber 88. The regulating chamber 88 is in communication with the intake manifold by means of a tube 89. A check valve seat conduit 90 is provided in the upper section of the housing 85 between the expansion chamber 87 and the fuel feed line between the fuel pump and carburetor, having a ball check valve 91 gravity-seated therein, and a return line 92 extends from the expansion chamber 87 to the fuel tank.

A plunger 93 supported centrally on the diaphragm 86 at a point intermediate its ends projects upwardly into the valve seat conduit 90 to unseat the check valve 91 when atmospheric pressure conditions are coupled to the regulating chamber 88 from the intake manifold. The portion 94 of the plunger 93 depending from the diaphragm through a sealing gasket in the lower wall of the housing 85 terminates in a lateral shoulder 95 disposed below the periphery of a lockout cam 96 on the throttle valve shaft 97 of the engine. The lockout cam 96 has a small relieved section 98 which faces the shoulder 95 when the throttle is closed.

In the operation of this embodiment, the presence of negative pressure conditions in the intake manifold when the engine is operating draws the diaphragm 87 and plunger 93 down from the position illustrated in Figure 4 to a position permitting the check valve 91 to seat and close off the valve seat conduit 90. The open condition of the carburetor throttle valve when the engine is operating under heavy load, as when the vehicle is travelling up an incline, disposes the larger radius portions of the lockout cam 96 toward the shoulder 95 of the plunger portion 94, maintaining the plunger in lowered position wherein the check valve is seated. When the intake manifold pressure collapses upon termination of engine operation, the plunger 93 is projected upwardly by the rising pressure on the lower face of the diaphragm 86 to unseat the check valve 91. The fuel pressure in the fuel feed line is therewith relieved through the valve seat conduit 90, the expansion chamber 87 and the return line 92 to the fuel tank.

While several preferred embodiments have been specifically shown and described herein, it is apparent that other modifications may be made in the invention without departing from the spirit and scope thereof, and it is desired, therefore, that only such limitations shall be placed thereon as are imposed by the prior art and are set forth in the appended claims.

I claim:

1. In combination with an internal combustion engine having fuel pump means, an intake manifold, a carburetor, and a fuel feed line between said fuel pump means and said carburetor, fuel pressure relief means for selectively reducing the pressure in said fuel feed line comprising fuel accommodating means communicating with said fuel feed line into which fuel may be displaced from said feed line, displaceable means regulating the volume of said fuel accommodating means directly communicating with said feed line, and means for subjecting said displaceable means to the pressure in said intake manifold to position said displaceable means to establish a minimum volume condition in said fuel accommodating means when the intake manifold pressure is low during operation of said engine and to position said displaceable means to increase the volume of said fuel accommodating means directly communicating with said fuel feed line when the pressure reaches a relatively higher value in said intake manifold upon cessation of engine operation.

2. In combination with an internal combustion engine having fuel pump means, an intake manifold, a carburetor, and a fuel feed line between said fuel pump means and said carburetor, fuel pressure relief means for reducing the pressure existing in said fuel feed line upon cessation of the operation of the engine comprising a fuel-receiving branch communicating with said fuel feed line into which fuel is displaceable for varying the effective volume of the fuel feed line between said fuel pump means and said carburetor, displaceable means for controlling the effective volume of said fuel-receiving branch means accessible to receive fuel from said fuel line, and means associated with said displaceable means rendering said displaceable means responsive to the pressure in said intake manifold so as to condition said displaceable means to expose a minimum volume of said fuel-receiving branch means to admission of fuel from said fuel feed line during occurrence of sub-atmospheric pressure conditions in said intake manifold and to increase the volume of said fuel-receiving branch means accessible to receive fuel from said feed line when the pressure in said intake manifold approaches atmospheric pressure.

3. In combination with an internal combustion engine having fuel pump means, an intake manifold, a carburetor, and a fuel feed line between said fuel pump means and said carburetor, fuel pressure relief means for reducing the pressure existing in said fuel feed line upon cessation of the operation of the engine comprising a fuel-receiving branch communicating with said fuel feed line into which fuel is displaceable for varying the effective volume of the fuel feed line between said fuel pump means and said carburetor, displaceable means for controlling the effective volume of said fuel-receiving branch means accessible to receive fuel from said fuel line, and means associated with said displaceable means rendering said displaceable means responsive to the pressure in said intake manifold so as to condition said displaceable means to expose a minimum volume of said fuel-receiving branch means to admission of fuel from said fuel feed line during occurrence of sub-atmospheric pressure conditions in said intake manifold while said engine is operating and to increase the volume of said fuel-receiving branch means accessible to receive fuel from said feed line when the pressure in said intake manifold approaches atmospheric pressure upon cessation of engine operation.

4. In combination with an internal combustion engine having fuel pump means, an intake manifold, a carburetor, and a fuel feed line between said fuel pump means and said carburetor, fuel pressure relief means for reducing the pressure established in said fuel feed line upon cessation of operation of the engine comprising expandible chamber means having a flexible diaphragm controlling the volume thereof, a conduit communicating said chamber with said fuel feed line, and regulating means intercoupled with said diaphragm and responsive to the

pressure in said intake manifold for positioning said diaphragm to establish a minimum volume condition in said expandible chamber upon occurrence of sub-atmospheric pressure conditions in said intake manifold incident to engine operation and to increase the volume of said expandible chamber when the pressure rises in said intake manifold upon cessation of engine operation and accommodate fuel from said fuel feed line reducing the pressure therein.

5. In combination with an internal combustion engine having a fuel pump, an intake manifold, a carburetor, and a fuel feed line between said fuel pump and said carburetor, fuel line pressure relief means including a pressure relief assembly having a rear chamber and a front chamber separated by a marginally supported peripheral diaphragm, means directly communicating said front chamber with said fuel feed line, means directly communicating said rear chamber with said intake manifold to subject the surface of said diaphragm facing said rear chamber to the pressure in said intake manifold for positioning said diaphragm to establish a selected minimum volume condition in said front chamber when sub-atmospheric pressure conditions exist in said intake manifold and shift said diaphragm to increase the volume in said front chamber when the pressure in said intake manifold approaches atmospheric conditions upon cessation of engine operation.

6. In combination with an internal combustion engine having a fuel pump, an intake manifold, a carburetor, and a fuel feed line between said fuel pump and said carburetor, fuel pressure relief means including a pressure relief assembly having a rear chamber and a front chamber isolated from each other, means directly communicating said front chamber with said fuel feed line, means communicating said rear chamber with said intake manifold, said front chamber having a flexible diaphragm for controlling the volume of front chamber accessible to receive fuel from said fuel feed line, and said rear chamber having a flexible diaphragm therein exposed to the pressure in said intake manifold, and means interconnecting said diaphragms for coordinating movement thereof, said diaphragms being positioned by sub-atmospheric pressure from said intake manifold in said rear chamber to establish a selected minimum volume condition in said front chamber and said diaphragms being shifted when the pressure coupled to said rear chamber from said intake manifold approaches atmospheric pressure upon cessation of engine operation to increase the volume of said front chamber exposed to receive fuel from said fuel feed line.

7. In combination with an internal combustion engine having fuel pump means, an intake manifold, a carburetor, and a fuel feed line between said fuel pump means and said carburetor, fuel pressure relief means for reducing the pressure existing in said fuel feed line upon cessation of the operation of the engine comprising a fuel-receiving branch communicating with said fuel feed line into which fuel is displaceable for varying the effective volume of the fuel feed line between said fuel pump means and said carburetor, displaceable means for controlling the effective volume of said fuel-receiving branch means accessible to receive fuel from said fuel line, means associated with said displaceable means rendering said displaceable means responsive to the pressure in said intake manifold so as to condition said displaceable means to expose a minimum volume of said fuel-receiving branch means to admission of fuel from said fuel feed line during occurrence of sub-atmospheric pressure conditions in said intake manifold and to increase the volume of said fuel-receiving branch means accessible to receive fuel from said feed line when the pressure in said intake manifold approaches atmospheric pressure, and means conditioned continuously during operation of said engine for restraining said displaceable means against alteration of said minimum volume condition to render said displaceable

means insensitive to transitory variations in intake manifold pressure.

8. In combination with an internal combustion engine having fuel pump means, an intake manifold, a carburetor, a fuel feed line between said fuel pump means and said carburetor and an ignition switch for said engine, fuel pressure relief means for reducing the pressure existing in said fuel feed line upon cessation of the operation of the engine comprising a fuel-receiving branch communicating with said fuel feed line into which fuel is displaceable for varying the effective volume of the fuel feed line between said fuel pump means and said carburetor, displaceable means for controlling the effective volume of said fuel-receiving branch means accessible to receive fuel from said fuel line, means associated with said displaceable means rendering said displaceable means responsive to the pressure in said intake manifold so as to condition said displaceable means to expose a minimum volume of said fuel-receiving branch means to admission of fuel from said fuel feed line during occurrence of sub-atmospheric pressure conditions in said intake manifold and to increase the volume of said fuel-receiving branch means accessible to receive fuel from said feed line when the pressure in said intake manifold approaches atmospheric pressure, and electromagnetic lockout means conditioned continuously while said ignition switch is close circuited to restrain said displaceable means against movement altering said minimum volume condition and render the same insensitive to transitory variations in intake manifold pressure.

9. In combination with an internal combustion engine having fuel pump means, an intake manifold, a carburetor, a fuel feed line between said fuel pump means and said carburetor, and a throttle valve for said engine, fuel pressure relief means for reducing the pressure existing in said fuel feed line upon cessation of the operation of the engine comprising a fuel-receiving branch communicating with said fuel feed line into which fuel is displaceable for varying the effective volume of the fuel feed line between said fuel pump means and said carburetor, displaceable means for controlling the effective volume of said fuel-receiving branch means accessible to receive fuel from said fuel line, means associated with said displaceable means rendering said displaceable means responsive to the pressure in said intake manifold so as to condition said displaceable means to expose a minimum volume of said fuel-receiving branch means to admission of fuel from said fuel feed line during occurrence of sub-atmospheric pressure conditions in said intake manifold and to increase the volume of said fuel-receiving branch means accessible to receive fuel from said feed line when the pressure in said intake manifold approaches atmospheric pressure, and magnetic lockout means conditioned by said throttle valve to restrain said displaceable means against movement altering said minimum volume condition and render the same insensitive to transitory variations in intake manifold pressure.

10. In combination with an internal combustion engine having fuel pump means, an intake manifold, a carburetor, and a fuel feed line between said fuel pump means and said carburetor, fuel pressure relief means for reducing the pressure in said fuel feed line upon cessation of the engine comprising expandible chamber means communicating with said fuel feed line, a marginally supported flexible diaphragm in said chamber means controlling the volume thereof accessible to said fuel feed line, normally seated check valve means between said chamber and said fuel feed line interrupting the communication therebetween, means projecting from said diaphragm for unseating said check valve means when said diaphragm is flexed in a preselected direction, and means subjecting said diaphragm to the pressure in said intake manifold for flexing said diaphragm in a direction to free said check valve to occupy its normally seated position upon occurrence of sub-atmospheric pressure conditions in said intake manifold incident to engine operation and to flex said diaphragm

to unseat said check valve and increase the volume of said expansible chamber means exposed to said fuel feed line when the pressure in said intake manifold approaches atmospheric pressure upon cessation of engine operation to admit fuel to said expansible chamber and relieve pressure in said fuel feed line.

11. In combination with an internal combustion engine having fuel pump means, an intake manifold, a carburetor, a fuel feed line between said fuel pump means and said carburetor, and an ignition switch for said engine, fuel pressure relief means for reducing the pressure in said fuel feed line upon cessation of the engine comprising expansible chamber means communicating with said fuel feed line, a marginally supported flexible diaphragm in said chamber means controlling the volume thereof accessible to said fuel feed line, normally seated check valve means between said chamber and said fuel feed line interrupting the communication therebetween, means projecting from said diaphragm for unseating said check valve means when said diaphragm is flexed in a pre-selected direction, means subjecting said diaphragm to the pressure in said intake manifold for flexing said diaphragm in a direction to free said check valve to occupy its normally seated position upon occurrence of sub-atmospheric pressure conditions in said intake manifold incident to engine operation and to flex said diaphragm to unseat said check valve and increase the volume of said expansible chamber means exposed to said fuel feed line when the pressure in said intake manifold approaches atmospheric pressure upon cessation of engine operation to admit fuel to said expansible chamber and relieve pressure in said fuel feed line, an electromagnetic coil disposed adjacent said diaphragm, magnetizable means fixed on said diaphragm, and means electrically connecting said electromagnetic coil with said ignition switch to energize said coil upon close circuiting of said ignition switch and magnetically attract said magnetizable member on said diaphragm toward said coil to restrain said diaphragm against check valve unseating movement during transitory small pressure increases in said intake manifold while said engine is operating.

12. In combination with an internal combustion engine having fuel pump means, an intake manifold, a car-

buretor, a fuel feed line between said fuel pump means and said carburetor, and a rotatable throttle valve and shaft therefor controlling fuel supply to said carburetor, fuel pressure relief means for reducing the pressure in said fuel feed line upon cessation of the engine comprising expansible chamber means communicating with said fuel feed line, a marginally supported flexible diaphragm in said chamber means controlling the volume thereof accessible to said fuel feed line, normally seated check valve means between said chamber and said fuel feed line interrupting the communication therebetween, plunger means projecting from said diaphragm for unseating said check valve means when said diaphragm is flexed in a pre-selected direction, means subjecting said diaphragm to the pressure in said intake manifold for flexing said diaphragm in a direction to free said check valve to occupy its normally seated position upon occurrence of sub-atmospheric pressure conditions in said intake manifold incident to engine operation and to flex said diaphragm to unseat said check valve and increase the volume of said expansible chamber means exposed to said fuel feed line when the pressure in said intake manifold approaches atmospheric pressure upon cessation of engine operation to admit fuel to said expansible chamber and relieve pressure in said fuel feed line, said throttle valve shaft having a cam thereon including a relieved peripheral portion, and said plunger means having a shoulder thereon projecting into proximity with said cam to be restrained by the unrelieved peripheral portions of said cam against movement shifting said diaphragm into check valve unseating condition during transitory small pressure increases in said intake manifold while said throttle valve is positioned to supply fuel to said carburetor, and said relieved peripheral portion of said cam being positioned relative to said throttle valve and to said shoulder to be disposed in the path of movement of said shoulder when said diaphragm and plunger means undergo check valve unseating movement to free said plunger means and diaphragm for unseating said check valve when said diaphragm is flexed in response to rising intake manifold pressure.
